UNITED STATES PATENT OFFICE.

JOSEPH GARAMI, OF NEWARK, NEW JERSEY, ASSIGNOR OF ONE-HALF TO SARA STEINER, OF NEW YORK, N. Y.

DISPLAY DEVICE.

Specification of Letters Patent. Patented July 29, 1919.

1,311,601.

Application filed August 26, 1918. Serial No. 251,462.

To all whom it may concern:

Be it known that I, JOSEPH GARAMI, a subject of the King of Hungary, residing at Newark, in the county of Essex and State of New Jersey, have invented new and useful Improvements in Display Devices, of which the following is a specification.

This invention relates to mechanical display devices, and the principal objects of the invention are:—(1) to provide a mechanically operated display device of a patriotic character to be used in connection with campaigns for the sale of Liberty Bonds and War Saving Stamps, and for securing contributions to the Red Cross and in analogous activities; (2) to provide a display device including oppositely rotatable disks on which may be painted or otherwise produced messages, pictures, or other data, the disks being so designed and arranged that when put in operation, the data or pictures on one disk will be displayed or visualized in proper sequence as answers or responses to the messages or matter provided on the other disk; and (3) to provide a display device of the foregoing character having mechanism for intermittently operating the data disks in opposite directions and also for producing the operation at the desired intervals of hands or arms adapted to indicate or point out certain data to which it is desired to call particular attention.

With the foregoing objects and others in view, the invention resides in the details of construction and in the arrangement and combination of parts hereinafter described, defined in the claims, and illustrated in the accompanying drawings, forming a part of this specification, it being understood that many changes may be made in the size and proportion of the several parts and in the details of construction within the scope of the claims appended hereto without departing from the spirit or sacrificing any of the advantages of the invention.

One of the many possible embodiments of the invention is illustrated in the accompanying drawings, in which:

Figure 1 is a view in front elevation of a display device constructed in accordance with the present invention.

Fig. 2 is a rear elevational view of the same, parts being broken away.

Fig. 3 is a similar view with additional parts broken away to better illustrate the

relative arrangement of interior working elements.

Fig. 4 is a cross sectional view, taken in the direction of line 4—4 of Fig. 3.

Fig. 5 is a fragmental rear elevational view, showing in particular the arrangement of parts by which the indicating arms and movable display elements are operated.

Fig. 6 is a top plan view of the device.

Fig. 7 is a detail view of the disk for actuating the indicating elements.

With more particular reference to the accompanying drawings, the numeral 8 denotes a base-plate or board to the front end of which is secured an upright face plate 9 ⁷⁰ which is produced preferably of card-board or similar material when the device is made relatively small in size for a window or indoor display, and which is made preferably of metal, wood, or other similar material ⁷⁵ when the device is constructed in relatively large size for an outdoor display. The plate 9 is preferably made or cut with its opposite side edges 10 and 10' inclining somewhat toward each other in irregular outline, as best ⁸⁰ shown in Fig. 1.

The top portions of these sides are cut out or fashioned in conjunction with the top edge 12 to produce the upper portion of the figures or likenesses A and B respectively. Between these figures, the top edge 12 is cut or made to provide the arc 13 of the circle or globe 14, which is produced between the figures, by means of painting, ⁹⁰ printing or otherwise. Within the circle ⁹⁰ representing the globe, there is painted or otherwise produced continental outlines or such parts thereof as may be necessary in order to illustrate the relative location of the United States and Germany. The figures or ⁹⁵ likenesses A and B are also preferably produced on the plate 9 by painting. In the present instance the figure A is produced or completed to represent Uncle Sam, while the figure B represents the over-seas military commander of Uncle Sam. As best ¹⁰⁰ shown in Fig. 4, the front plate 9 is braced with respect to the bottom plate 8 by means of a side plate 15.

Secured by means of screws as 16 or otherwise to the bottom plate 8, spacedly behind the face plate 9, is a U-shaped frame, the sides 17 and 18 of which lie parallel to the front plate 9. Journalled at 19 in the side ¹⁰⁵ 18 and extending transversely through a ¹¹⁰

suitable opening in the opposite side 17 is a shaft 20, the forward end of which at 21 is reduced and made square in form to enter a corresponding opening provided centrally in a removable display disk plate 22. In the front plate 9, opposite the shaft 20, is an opening 23 in which is loosely arranged a pin 24, the inner end of which is reduced and threaded within the square end 21. Engaged with this pin is a collar or flange 25 adapted to bear against the display disk 22 to secure the same in position upon the shaft 20 for rotation therewith. Loosely mounted upon the shaft 20 is a sleeve 26 which also extends through the opening in the side plate 17 and to which is secured in front of said side plate a collar 27. Loosely and centrally mounted around the shaft 20 and pinned to the said collar 27 is a second disk display plate 28, of the same size as the plate 22. Both of the disk plates are of such size that their marginal face edges will be visualized above the arc edge 13 of the front plate 9 with respect to which they are concentrically mounted. The disk plates 22 and 28 each have portions of their circumference concentrically cut away as at 29 and 30 respectively, the depth of the cuts being such as to synchronize the edges thereof with the top arc edge 13 of the face plate 9, and so that the uncut marginal edges 31 and 32, respectively, of the plates, may be displayed above the said arc edge 13.

Fast upon the sleeve 26 behind the side 17 of the U-shaped member is a pinion 33; while fast upon the shaft 20 beyond the sleeve is another pinion 34. Adapted to engage the pinion 33 is a segmental gear 35, fast on a shaft 36, which is rotatably journaled in and between the sides 17 and 18. In mesh with the pinion 34 is a gear 37 carried by shaft 38 also journaled in and between the sides 17 and 18. Motion is imparted to gear 37 by a segmental wheel 39 carried by the shaft 36. Under this arrangement of parts and gearing, the rotary motion of the shaft 36 is employed to rotate the disks 22 and 28 intermittently in opposite directions, the relative arrangement of the disks being such that as the reduced peripheral edge 29 of the disk 22 passes the arc 13, the marginal edge 32 of the other disk 28 will be displayed above said arc 13; and conversely, also, that as the reduced peripheral edge 30 of the disk 28 moves behind the arc 13, the marginal edge 31 of the front disk 22 will be displayed above said arc. Also journaled in and between the sides 17 and 18 in proper spaced apart positions, are the shafts 40, 41, 42, and 43, each provided with a spur gear as 44 and a pinion as 45, the pinion on each shaft being in mesh with the spur gear on the next succeeding shaft as follows: that on shaft 40 being in mesh with the spur gear on shaft

41, that on shaft 41 being in mesh with the spur gear on shaft 42, and that on shaft 42 being in mesh with the spur gear on shaft 43, while that on shaft 43 drives the spur gear 46 carried by the shaft 36, whereby the latter is driven. In mesh with the spur gear on shaft 40 is a pinion 47 carried by the driving shaft 48, which is also journaled for rotation in the sides 17 and 18. This shaft 48 may be driven by any suitable source of power such as a motor (not shown); and it will be obvious that the train of reduction gearing just described is employed in order that the display disks 22 and 28 may be given relatively slow movement.

The shaft 36, which carries the segmental gears 35 and 39, projects beyond the side 18 where it is provided with a disk or cam device 49 having two peripheral faces, 50 and 51. Pivoted to the side 18 at 52 is a lever 53 having a lug 54, which rides upon the cam face 51 to engage the recesses 55 therein. Pivotedly connected with this lever at 56 is a connecting rod 57, the opposite end of which is pivotally connected at 58 to the crank arm 59, the shaft for which projects forwardly through the face plate 9, and to which is attached on the front side thereof the arm 60 of the figure or likeness B. Fast also with the shaft for the crank arm 59 is a lever 61, to which is pivotally connected at 62 a connecting rod 63, which in turn is pivotally engaged at 64 with the crank 65 of the shaft 66, on which is carried a disk display plate 67, the said shaft 66 being rotatably secured in the face plate 9. To the forward end of the rod 63 is pivoted at 68 the end of a bell crank lever 69, supported on a pin 70 projecting from the rear side of the face plate 9. The opposite end of this bell crank lever is provided with a slot 71, in which works a pin 72 carried by the triangular-shaped display plate 73. In this display plate are alined slots as 74 receptive of pins as 75 projecting from the rear of the face plate 9, and by which the display plate is mounted for vertical sliding movement under the operation of the bell crank lever. Through the face plate 9 in front of the triangular shaped display plate 73 is an elongated arcuate opening 76. This display plate 73 is herein shown as having provided on its front face the word "Peace", in such position that when the display plate is in elevated position, the said word "Peace" will be concealed behind the face plate, and when in lowered position, the said word will be displayed through the opening 76.

Cut also through the face plate 9 in front of the display disk 67 is an opening 77. On the front side of this display disk, as herein shown, are the words "Autocracy" and "Democracy," the same being arranged on

said plate in such manner with respect to said opening 77, that when one of the words is displayed through said opening, the other is concealed behind the front plate. Now 5 the said display plates 67 and 73 are operated by the mechanism controlled by the cam disk 49 in such manner that when "Peace" and "Democracy" are concealed behind the front plate 9, the word "Autocracy" 10 will be displayed; and conversely, that when "Autocracy" is concealed, the words "Peace" and "Democracy" will be displayed.

Riding on the cam face 50 is the rounded end 78 of the lever 79, pivoted at 80 to the 15 side 18. Pivotedly engaged with this lever at 81 is a connecting rod 82, which is pivoted at 83 to the crank 84, the shaft 85 of which projects through the face plate 9, and carries on the front side thereof the arm 86 for the 20 figure or likeness A. Now the relative arrangement of the said arms 60 and 86 and the mechanism for operating the same are such that each will be elevated to indicate or point out the marginal edge of the revolving 25 disk as it is displayed above the arc 13. Thus, for instance, when any message or other data is displayed on the marginal edge 32 of the disk 28, which revolves away from the figure B, the arm 60 of said figure will 30 be elevated to indicate the same or such parts thereof as it is desired especially to point out; and similarly, when messages or data 35 painted on the marginal edge 31 of the other disk 22, which rotates away from the figure A, is displayed, the arm 86 will be elevated to indicate the same or such parts thereof as desired.

Now in the present embodiment of the invention, on the marginal edge 32 there may 40 be painted or produced any suitable message from the figure B requesting troops, supplies, or equipment; and on the marginal edge 31 may be painted or otherwise produced pictures of ships, troops, cannon and 45 the like, so that when the device is in operation, the same will appear as an immediate response from figure A to the message of figure B. The relative arrangement of parts is further such that when the message 50 of request is displayed, and pointed out by the arm of the figure B, "Autocracy" will be displayed through the opening 77 of the front plate 9; and also that when the responding message on marginal edge 31 55 passes or has passed from the figure A to figure B, "Democracy" and "Peace" will be displayed instead of "Autocracy."

Having thus described my invention, what I claim is:—

60 1. A display device of the character described including a base-plate, a face-plate rising therefrom and provided with confronting figures and a curved top edge therebetween, movable indicating elements combined with the figures to point out displayed

parts, a pair of independently rotatable disks arranged behind the face-plate parallel therewith and provided with marginal portions adapted to be displayed above the curved top edge, mechanism for rotating 70 said disks in opposite directions, and means operable by said mechanism for actuating said movable indicating elements in timed relation with respect to the rotation of said disks.

2. A display device of the character described including a base-plate, a face-plate rising therefrom and provided with a curved top edge and with openings, a pair of rotatable disks mounted behind said face-plate 80 in parallelism therewith and provided with marginal portions adapted to be displayed above the curved top edge, movable indicating elements combined with said face-plate on the front side thereof, movable display 85 plates arranged on the rear side of said face-plate to display features or data behind the openings therein, mechanism for rotating said disks in opposite directions, and means operable by said mechanism for actuating 90 said indicating elements and said display plates in timed relation with respect to the rotation of said disks.

3. In a display device of the character described, a face-plate provided with a 95 curved top edge forming a segment of a circle and with a figure outstanding on each side of said segment, movable arm elements for said figures on the front side of said face-plate adapted to point out displayed 100 parts, a pair of rotatable disks arranged behind said face-plate and provided with marginal portions adapted to be displayed above said curved top edge, mechanism for rotating said disks so that the matter on the 105 marginal portion of one disk may appear as responsive to that on the marginal portion of the other disk, and means connected with said arm indicating elements and adapted to be operated by said mechanism whereby 110 to acuate said arm indicating elements in timed relation with respect to each other and also with respect to the rotation of said disks.

4. In a device of the character described, 115 a face-plate formed with a curved top edge comprising the segment of a circle and with a figure outstanding on each side of the segment, said face-plate being provided with openings, movable arm elements combined 120 with said figures on the front side of said face-plate, a pair of disks rotatably mounted behind said face-plate in parallelism therewith, said disks being formed with marginal portions adapted to be displayed above the 125 curved top edge, movable display plates arranged behind said face-plate to display matter through the openings therein, mechanism for rotating said disks, and means operable by said mechanism for controlling 130

the operation of said indicating arm elements and said display plates in timed relation with respect to the rotation of said disks.

5. In a display device of the character described, the combination of a face-plate provided with movable elements, a pair of rotatable disks arranged behind said face-plate in parallelism therewith to display matter above the top edge of said face-plate, mechanism for intermittently rotating said disks in opposite directions, and means connected with said movable elements and operated by said mechanism by which to 10 actuate said movable elements in timed relation with respect to each other and with respect to the rotation of said disks.
6. In a display device of the character described, the combination of a face-plate provided with movable elements, a pair of display disks arranged behind the face-plate and provided with portions adapted to be displayed above the top edge of the face-plate, mechanism for intermittently rotating 15 said disks in opposite directions, and means connected with said movable elements and controlled by the operation of said

mechanism by which to actuate said movable elements in timed relation with respect to the intermittent movements of said disks. 30

7. In a display device of the character described, the combination of a face-plate provided with openings therethrough, movable indicating elements arranged on the front side of said face-plate, movable display 35 plates arranged on the rear side of said face-plate adapted to display matter through the openings therein, a pair of rotatable disks mounted behind said face-plate in parallelism therewith, said disks being provided 40 with marginal portions adapted to display matter above the top of said face-plate, mechanism for intermittently rotating said disks in opposite directions, and means connected with said movable elements both on 45 the front and on the rear sides of said face-plate and controlled by the operation of said mechanism by which to actuate said movable elements in timed relation with respect to each other and with respect to the movements of said disks. 50

In testimony whereof I have signed my name to this specification.

JOSEPH GARAMI.
